UNITED STATES PATENT OFFICE.

SWAN ANDERSON, OF MINNEAPOLIS, MINNESOTA.

STEAM GENERATOR.

Application filed June 23, 1927. Serial No. 200,813.

The object of this invention is to provide an efficient steam and hot water generator of novel and improved construction which will rapidly heat hot water to generate steam under pressure by use of a minimum amount of heat.

It is more specifically the object of this invention to provide certain improvements on my "steam generator" patented by me on October 14, 1919, Patent No. 1,318,825.

With these and other objects in view, my invention consists in the novel parts and novel combinations of parts hereinafter claimed and described in connection with the accompanying drawings, wherein like reference characters refer to the same or similar parts throughout, and in which,

Fig. 1 is a view in front elevation of the device with certain of the parts broken away and other parts shown in section;

Fig. 2 is a view in side elevation of the device illustrated in Fig. 1;

Fig. 3 is a horizontal section taken on the line 3—3 of Fig. 2, as indicated by the arrows, and,

Fig. 4 is a vertical section taken on the line 4—4 of Fig. 2, as indicated by the arrows.

Referring to the drawings, a base 5 is illustrated forming four leg pedestals spaced apart from each other, disposed in substantially rectangular arrangement and having outer sides and a bottom connecting the same. Resting on top of the pedestals are two hollow front legs 6 and 7, and two hollow rear legs 8 and 9. The said legs extend vertically upwardly from base 5 and are so spaced in respect to each other as to form corners of a rectangle. The two rear legs 8 and 9 are cut away at their facing sides to receive the ends of a casting 10 which is secured to said legs and extends between the same to the back of the generator. The casting 10 is preferably cored out to form a series of horizontal ducts 11 situated one on top of another, each duct being of substantially square shape in vertical cross section and the various ducts being arranged in stepped relation to one another so that they slant forwardly and upwardly from their rear edges. Facing sides of the front legs 6 and 7 are cut away to receive the ends of a casting 12, which is secured to said legs and extends between the same at the front of the generator. Casting 12 has a plurality of ducts 13 hereinafter termed V-shaped ducts

formed therein preferably by coring out the casting. The ducts 13 are of substantially square shape in vertical transverse cross section, while they are of substantially V-shape in vertical longitudinal cross section, the pointed portion of the V being centrally and downwardly disposed in the casting. The various V-shaped ducts 13 are formed one on top of each other in stepped relation and they also are inclined upwardly and forwardly from their rear edges. A plurality of sets of tubes 14 extend between and connect the horizontal ducts 11 with the V-shaped ducts 13, the said tubes having their rear ends secured in a plurality of openings formed in the forward sides of ducts 11 and having their forward ends secured in a plurality of openings formed in the rear sides of ducts 13. The V-shaped ducts 12 are disposed at a higher level than the horizontal ducts 11 and, accordingly, the various tubes 14 are inclined upwardly and forwardly from their rear ends. Each set of tubes preferably forms two rows of tubes 14 which extend between one of the horizontal ducts and one of the V-shaped ducts, and the tubes in each row are horizontally aligned at their ends connected to the horizontal ducts 11 while the tubes in each row are arranged in V-formation at their ends connected to the V-shaped ducts 13. The horizontal ducts 11 communicate with the rear legs 8 and 9, the tubes 14 afford communication between respective horizontal ducts 11 and V-shaped ducts 13, while the V-shaped ducts 13 communicate with the front legs 6 and 7. It will be understood that the number of ducts 11 and 13, the number of sets of tubes 14, the number of rows of tubes in each set and the number of tubes in each row may be varied as desired.

A series of rearwardly projecting steps 15 are provided in the front legs 6 and 7 adjacent their top ends to form a plurality of expansion chambers of gradually greater size toward the tops of the legs 6 and 7. The front legs 6 and 7 on the sides facing the rear legs 8 and 9 respectively are bossed up at spaced points adjacent their upper ends and the bossed portions are apertured to receive the forward ends of a series of horizontally disposed tubes 16, 17, 18 and 19. One of the bosses is formed in each of the legs 6 and 7 on each step 15. Respective tubes 16, 17, 18 and 19 extend

rearwardly between the leg 6 and leg 8 and between leg 7 and leg 9 respectively, at the sides of the generator, and the said tubes are secured at their ends in spaced bossed openings formed in the legs 8 and 9 adjacent their upper ends. The pipes 16, 17, 18 and 19 will afford communication between the front and rear legs. It will be understood that the number of steps 15 and the number 5 of tubes 16, 17, 18 and 19 or corresponding tubes can be varied as desired. A dome 20 forming a steam chamber is secured to the upper ends of the various legs 6, 7, 8 and 9 by means of bolts 21 screwed in threaded 10 bolt holes in the tops of the legs and the said legs communicate through apertures 20^a at the corners of said dome with the interior of the dome. The dome 20 has a substantially horizontal top portion and is provided 15 with an upwardly and centrally beveled bottom portion extending centrally from the inner sides of said legs. A plurality of vertical posts 22 are provided between the top and bottom portions of dome 20 at spaced 20 intervals to brace and strengthen the dome. An outlet conduit 23 is secured in a central apertured boss at the top of dome 20 and the said conduit leads off to one side of the dome.

25 The various ducts 11 and 13 are provided with threaded apertures 11^a and 13^a respectively at their outer sides facing the openings formed therein to receive the ends of the various tubes 14, and the said apertures are closed by threaded plugs 24 which are formed to receive a wrench to screw the same tightly in place within the apertures. The said apertures 11^a and 13^a are of considerably greater diameter than the diameter 30 of the pipes 14, whereby tools may be inserted through the apertures for swaging the ends of the tubes 14 to the inner sides of the various ducts or for insertion or removal of the various tubes. Similar threaded openings 35 are provided in the outer sides of the various legs 6, 7, 8 and 9 and facing the openings receiving the ends of the various tubes 16, 17, 18 and 19 for reception of threaded plugs 25. The said openings are of greater diameter than the diameter of 40 the tubes 16, 17, 18 and 19, whereby by removal of the plugs 25, tools may be inserted through the various plug apertures for swaging the ends of the tubes 16, 17, 18 and 19 45 or for insertion or removal of the various tubes. Inlet conduits 26 are secured in bossed openings adjacent the bottoms of legs 8 and 9 at the rear sides thereof for the admission of cold water to the generator.

50 A substantially rectangular casing 27 is provided which fits on top of the base 5 and houses the generator. The casing is rearwardly offset adjacent its top end at the rear side thereof at 28 to form an air passage leading from the interior portion of

the generator between the various legs, to the top of the casing. The upper end of the casing 27 is spaced some little distance above the dome 20 of the generator and is provided with an upwardly extending 70 flange 29 at its center to which a discharge flue 30 is connected. Suitable apertures are provided in the casing 27 through which the offtake conduits 23 may extend, while in the embodiment shown, the casing is provided with apertures through which the plugs 25 in the front legs 6 and 7 may extend. Doors 31 may be provided at the front of the casing for access to heating means (not shown) which is adapted to be 75 placed within the base 5.

80 A plurality of deflector plates 32 and 33 are provided which rest on top of the various sets of tubes 14 and are secured thereto in staggered relation to produce a circuitous circulation of hot air from the lower tubes to the top tubes. The plates 32 rest on alternate sets of tubes 14 and extend from the forward sides of ducts 11 forwardly past the center of the generator. The plates 33 rest on alternate sets of tubes 14 from the tubes on which plates 32 rest and extend from the rear sides of alternate ducts 13 rearwardly past the center of the generator. The plates 32 and 33 are alternately 90 arranged in respect to each other on the various sets of tubes 14 and the plates are shaped to contact the top surfaces of the various tubes 14 upon which they rest. The rear ends of plates 32, accordingly, will be 100 substantially straight while their forward ends will be V-shaped. Plates 33 will be pronounceably V-shaped at their forward ends and will be less pronounceably V-shaped at their rear ends. Preferably no plate is 105 placed on top of the uppermost set of tubes 14.

110 In practice, a burner or other heating device will be situated within the outline of the casing 27 below the generator and water admitted through inlet 26 will be maintained in the generator to stand at a level slightly below the tops of the various legs. Due to the construction of the various plates 32 and 33, hot gases from the burner 115 will follow a tortuous path around the various tubes 14 as indicated by the arrows, Fig. 2. Also due to the V-shaped construction of the major portions of the plates 32 and 33, the hot air will be deflected outwardly to the side tubes 14 of the generator causing the heat from the burner which naturally is greatest at the center of the generator, to be distributed evenly around all the various tubes. Water admitted to the rear legs 8 and 9 will circulate from the said legs to the ducts 11 and thence through the various tubes 14 to the ducts 13. Due to the fact that the tubes 14 slant upwardly from their rear ends to their forward ends, the ex- 120 130

- pansion of the water in the tubes, as the same are heated, will cause the water to seek a higher level thereby creating a continuous forward circulation of water and steam through the tubes. Due to the V-arrangement of the forward ends of the tubes 14, some of the water and steam generated thereby will be discharged at lower points in the ducts 13 than other water and steam.
- 5 The V-shape of the ducts 13 will cause the water and steam to circulate from the central or pointed portions of the ducts sidewardly to the front legs 6 and 7, inasmuch as the ends of the ducts will be at a higher 15 vertical level than the central portions thereof. There will thus be a continuous circulation of water through the tubes and through the various ducts 11 and 13 and, accordingly, any condensation of solid material caused from heating the water will 20 not remain in the tubes 14 to cause the same to become clogged. The water and steam after circulating to the front legs 6 and 7 will rise upwardly therein to the tops thereof, whereupon the various successively larger 25 chambers formed by the step construction 15 at the tops of the forward legs will provide plenty of room to take care of the expansion of the water through heating.
- 30 From the tops of the legs 6 and 7 the steam that is generated will pass upwardly into the chamber formed in the top dome 20 and thence outwardly through the discharge outlet 23. Water and steam will freely circulate between the front legs 6 and 7 and the rear legs 8 and 9 through the tubes 16, 35 17, 18, and 19, thereby permitting a continuous circulation of water through the whole generator. Any steam which may 40 accuinulate at the tops of legs 8 or 9 may pass readily into the chamber formed in dome 20. The bottom of dome 20 is upwardly and centrally beveled to permit any condensation of water formed by the steam 45 generated to run down into the various legs. There will thus be no water standing in the dome 20 at the center thereof under normal conditions and, accordingly, steam issuing from outlet 23 will be quite dry.
- 50 By removal of the casing 27, the various plugs 24 and 25 may be removed to replace or repair the tubes 14 and the tubes 16, 17, 18 and 19. Plugs 34 are preferably provided at the lower forward sides of the 55 legs 6 and 7 and by removal of these plugs and by removal of the inlet conduits 26 access can be had to the lower interior of the various legs to permit the same to be readily cleaned out. If desired, of course, 60 the generator may be used strictly as a water heater, whereupon in operation the generator will be completely filled with water. It will be understood, that if desired the legs 8 and 9 may be used as front
- legs while the legs 6 and 7 may be used as rear legs. Also if desired, the various ducts 11 and 13 may be formed as separate units rather than being formed as parts of the castings 10 and 12.
- Due to the construction of the generator 70 the same will heat water very rapidly with an expenditure of a minimum amount of heat and steam will be quickly generated under high pressure.
- The efficiency of the generator has been 75 demonstrated in actual practice.
- It will, of course, be understood that various changes may be made in the form, details, arrangement and proportions of the 80 various parts without departing from the scope of the present invention.
- What is claimed is:
1. A steam generator having in combination a chamber, means for supplying water to said chamber, a plurality of horizontally disposed ducts leading from said chamber, a pair of upstanding hollow legs spaced from said ducts and from each other, a plurality of ducts of V-shape in longitudinal cross section extending between and connecting said legs and a plurality of sets of tubes 85 extending between and connecting said horizontal and V-shaped ducts, each set of tubes extending upwardly from a lower horizontal duct to a higher V-shaped duct, and discharging means leading from said pair of legs. 90
  2. The structure defined in claim 1, the tubes in each set being arranged in V-formation at their ends joining said V-shaped ducts. 100
  3. A steam generator having in combination four hollow legs spaced apart from each other and disposed in substantially rectangular arrangement, a plurality of substantially horizontally disposed ducts connecting a pair of said legs, a plurality of ducts of substantially V-shape in vertical longitudinal cross section connecting the opposite pair of legs and a plurality of sets of tubes extending between and connecting said horizontal ducts and said V-shaped ducts, each set of tubes extending from a lower horizontal duct to a higher V-shaped duct, 110 and the tubes in each set being arranged in V-relation at their ends joining said V-shaped ducts. 115
  4. A steam generator having in combination four hollow legs spaced apart from each other and disposed in substantially rectangular arrangement, a plurality of substantially horizontally disposed ducts connecting a pair of said legs, a plurality of substantially V-shaped ducts in vertical longitudinal cross section connecting the opposite pair of legs, a plurality of sets of tubes extending between and connecting said horizontal ducts and said V-shaped 120
  - 125

ducts, each set of tubes extending from a lower horizontal duct to a higher V-shaped duct and the tubes in each set being arranged in V-relation at their ends joining said V-shaped ducts, said last mentioned legs having a plurality of steps adjacent their top ends projecting outwardly vary-

ing distances to form expansion chambers of successively enlarged size toward their top ends and conduits extending between said steps of said last mentioned legs to said first mentioned legs.

In testimony whereof I affix my signature.

SWAN ANDERSON.
